UNITED STATES PATENT OFFICE.

WILLARD A. KITTS, JR., OF OSWEGO, NEW YORK.

HAT-FASTENER.

1,081,967.

Specification of Letters Patent.

Patented Dec. 23, 1913.

Application filed January 23, 1911. Serial No. 604,269.

To all whom it may concern:

Be it known that I, WILLARD A. KITTS, Jr., of Oswego, in the county of Oswego, in the State of New York, have invented new and useful Improvements in Hat-Fasteners, of which the following, taken in connection with the accompanying drawings, is a full, clear, and exact description.

This invention relates to certain improvements in ladies' hat fasteners adapted to be incorporated in the frame or inner band of the hat, and provided with suitable fastening spurs or fingers adapted to be projected into the hair to hold the hat in its adjusted position.

The main object is to conceal the fastening means entirely within the inner band of the hat, and at the same time to render the prongs or spurs adjustable so that they may be projected into the hair or withdrawn at will, thereby avoiding mutilation of the hat and dangers incidental to the use of the usual hat pin. In other words, I have sought to retain the hat in place by flexible spurs or prongs (preferably of light spring metal) adapted to be withdrawn into and projected inwardly from a suitable sheath which is secured in the band of the hat, the sheath serving to conceal the spurs or prongs when the latter are withdrawn from use, and also to deflect the points of the spurs or prongs inwardly from the sheath when adjusted for use.

Other objects and uses relating to specific parts of the device will be brought out in the following description.

In the drawings: Figure 1 is a top plan of the detached hat fastener showing the spurs or prongs adjusted for use. Fig. 2 is a side elevation of the same. Fig. 3 is an inner face view of a portion of the fastener showing one of the prongs and guide opening through which it is projected. Figs. 4 and 5 are sectional views taken on line 4—5, Fig. 4, the prong or spur being projected inwardly in Fig. 4, and withdrawn or concealed within the sheath in Fig. 5. Figs. 6 and 7 are sectional views taken respectively on lines 6—6, and 7—7, Fig. 2.

As illustrated in the drawings, this hat fastener comprises a segmental sheath —1— and a plurality of spurs or prongs —2— which are movable in suitable guide openings —3— in the inner side of the sheath —1— and are connected for simultaneous movement by a segmental bar —4—. All of

these parts are made of comparatively thin spring metal preferably flat in cross section, and are therefore light and flexible so as to readily conform to the shape of the band of the hat, to which the sheath is adapted to be secured. This sheath preferably consists of a thin spring metal segment —5— and suitable guide loops —6— secured thereto for receiving and guiding the movable segmental bar —4—. The segment —5— is of somewhat greater width than the bar —4— and adapted to be secured by stitches or otherwise to the inner band of a lady's hat, and for this purpose is provided at intervals along its edges with apertures —7— for receiving the stitches. The loops —6— are secured to and project outwardly from the outer face of the segmental band —5— and are spaced some distance apart to form guides for the bar —4— and bases of the prongs —2—. The segmental bar —4— encircles the inner band —5— concentric therewith and midway between its longitudinal edges, and is slideable longitudinally in the guides —6— for projecting the spurs or prongs —2— through and withdrawing them from the openings —3—, said bar being operated by a suitable hand piece —8—, as best seen in Figs. 2 and 7. The prongs or spurs —2—, which are made of thin flat spring metal, are secured at one end by suitable fastening means, as rivets —9—, to the inner face of the bar —2—, while their opposite free ends are pointed and normally rest in their respective openings —3—, sufficient space being left between the band —5— and bar —4— to receive between them the spurs or prongs —2—, when the latter are withdrawn from their operative positions.

When the device is secured in the band of the hat in any well known manner, not necessary to herein illustrate or describe, the rod or bar —4— is moved in one direction by the hand piece —8— to simultaneously withdraw all of the spurs or prongs —2— back into the sheath, as shown in Fig. 5, so as to permit the hat to be placed in suitable position upon the head, after which the bar —4— may be shifted in the opposite direction, thereby causing the points of the prongs or spurs —2— to ride inwardly through their respective openings —3— which are arranged to deflect the prongs inwardly from the band —5—, as clearly shown in Figs. 1 and 4, to enter the hair and

thereby retain the hat upon the head of the wearer, the operation being reversed when desired to remove the hat.

The invention is not limited to the exact form of spurs, nor to the means herein shown and described for adjusting them as it is evident that such construction and adjustment may be varied materially within the scope of the appended claim without departing from the main spirit of the invention, which is to provide an attachment for ladies' hats having movable spurs or prongs adapted to be projected into and withdrawn from the hair at will.

15 What I claim is:

A hat fastener formed of flat thin spring metal comprising a relatively wide arcuate member having a plurality of slots disposed mid-way between the side edges thereof, the opposite side walls of the slots being inclined in the same direction, a plurality of transversely-extending guides secured to the

outer face of the member, one guide being positioned rearwardly and adjacent to each of said slots, a relatively narrow arcuate bar 25 mounted in said guides and shiftable therein in both directions on the arcuate member, a plurality of flexible flat spurs flatly connected at their outer ends to the inner face of said bar, the free ends of said spurs being projected through the slots in the arcuate member as the bar is moved in one direction, said spurs lying flatly between the bar and member when withdrawn from the slots by a movement of the bar in the other direction, and a depending hand piece carried by said bar substantially mid-way between its ends.

In witness whereof I have hereunto set my hand on this 20th day of January 1911.

WILLARD A. KITTS, JR.
